ROAD JOINT END SEAL

Robert R. Robertson, Chicago, Ill., assignor to
 The Translode Joint Company, Chicago
 Heights, Ill., a corporation of Illinois

Application May 3, 1937, Serial No. 140,284

11 Claims. (Cl. 94—18)

This invention relates to transverse road joints and more particularly to end seals for closing the outer ends of the joints adjacent the road shoulder. The end seal for the transverse road joint 5 includes an inherently expandable precompressed sealing pad of sponge rubber or the like which is enclosed by a metal shield or casing the ends of which are anchored in adjacent concrete road slabs on opposite sides of the joint which is to 10 be sealed thereby affording an arrangement whereby contraction or expansion of the road slabs due to temperature changes or other causes will actuate the steel casing or shield to cause the pre-compressed seal pad to maintain a sealing 15 contact with the end of the joint, at all times, regardless of whether the joint is opened or closed by the action of the road slabs.

It is an object of this invention to provide a transverse road joint with an end seal positioned 20 across the outer end of the joint and connected with the road slabs on adjacent sides of the joint for maintaining a substantially permanent seal at the outer end of the joint adjacent the road shoulder.

It is also an object of this invention to provide an end seal for a transverse road joint, said seal being positioned across the outer end of the joint and overlapping the road slabs on opposite sides of the joint in a manner to permit actuation of 30 the seal by the movement of the road slabs caused by temperature changes or other causes.

It is a further object of this invention to provide an improved end seal for transverse road joints, said end seal including inherently expandable pre-compressed material which is held 35 in position by closure means connected with and operable by the road slabs on adjacent sides of the joint.

It is furthermore an object of this invention to 40 provide an end seal for a transverse road joint, said end seal including a shell, the ends of which are anchored in the road slabs on opposite sides of the joint, with said shell enclosing a pre-compressed inherently expandable sealing material 45 adapted to completely fill the shell at all times and maintain a tight seal against the end of the joint, with either the compression or the elongation of steel shell caused by the expansion or the contraction of the road slabs due to temperature changes or other causes.

It is an important object of this invention to 50 provide an improved and simplified form of end seal for a transverse road joint, said seal including a metal shell, the end flanges of which are anchored in adjacent road slabs on opposite sides

of the seal, with the shell enclosing a pre-compressed inherently expandable sealing material which will maintain a seal at the end of the joint at all times.

Other and further important objects of this 5 invention will be apparent from the disclosures in the specification and the accompanying drawing.

The invention (in a preferred form) is illustrated in the drawing and hereinafter more fully 10 described.

On the drawing:

Figure 1 illustrates a horizontal fragmentary section through an improved end seal embodying the principles of this invention and shown in 15 position adjacent the outer end of a road expansion joint embedded between concrete road slabs.

Figure 2 is a reduced fragmentary horizontal sectional view similar to that illustrated in Figure 1 but showing the road slabs contracted to transversely tension the steel casing to cause a slight inward flexing of the main plate of the seal to compress the sealing material against the 20 end of the joint as the sealing material expands 25 to fill the steel casing.

Figure 3 is a horizontal sectional view similar to Figure 2 but showing the road slabs expanded to compress the expansion joint and cause the steel casing to bow outwardly bringing the sides 30 of the sealing material closer together and increasing the thickness to maintain the tight seal against the end of the expansion joint.

Figure 4 is an end elevational view of the road seal removed from the concrete and showing a 35 supporting shoe engaged with an expansion joint illustrated in dotted lines.

Figure 5 is a fragmentary vertical sectional view taken on line V—V of Figure 4.

Figure 6 is a top plan view of the end seal cas- 40 ing with the sealing material omitted.

As shown on the drawing:

The reference numeral 1 indicates a pair of adjacently positioned concrete road slabs having embedded therebetween a transversely disposed 45 road expansion joint comprising a metal core plate 2 having cemented on one side thereof a pre-cast or pre-formed compressible filler board 3. The expansion joint extends transversely between the road slabs 1 with the outer end of the 50 expansion joint exposed at the shoulder of the road.

For the purpose of sealing up the outer end of the expansion joint to prevent water and the shoulder material from working in between the 55

expansion joint members and the concrete slabs, the outer end of the joint is sealed by an improved sealing mechanism comprising a steel casing constructed out of galvanized sheet steel 5 and consisting of a main seal plate 4 having the side margins thereof deflected to provide closure flanges 5. The margins of the inclined side flanges 5 are provided with integral anchoring lugs or blades 6 of substantially dovetail shape. 10 Integrally formed along the lower edge of the seal plate 4 is an intermediate base flange 7 and two side base flanges 8 which are narrower than the width of the intermediate base flange 7. Disposed within the steel casing, on the inner 15 side of the plate 4 and between the side flanges 5, is a sealing pad constructed of sponge rubber or other suitable material, which is inherently expansible when compressed. The lower end of the sealing pad or cushion 9 seats on the base 20 flanges 7 and 8 with the intermediate base flange projecting beyond the thickness of the sealing pad 9, as clearly illustrated in Figure 5, to permit the projecting end of the intermediate base flange 7 to be spot welded or otherwise secured 25 to the bottom of a channel section 10, of a supporting shoe. The side walls of the channel 10 extend upwardly and then are bent downwardly upon themselves, as clearly illustrated in Figure 4, to form the double thickness walls or flanges 30 11. Integrally formed with the lower margins of the outer walls of the side flanges 11 of the channel member 10 are two base flanges 12. The base flanges 12 are provided with apertures for the reception of anchoring stakes, which have 35 been omitted. When the sealing unit is engaged against the outer end of the expansion joint and against the outer sides of the road slabs 1, the supporting shoe for the sealing unit projects into a position to permit the core plate 2 and the filler 40 board 3 to be seated therein, as illustrated in Figure 4, so that the joint forming mechanism, the supporting shoe, and the end seal unit may all be supported upon the road sub-grade prior to the pouring of the concrete for forming the 45 road slabs 1. With the pouring of the concrete to embed the expansion joint, the concrete embeds the anchoring lugs 6 and portions of the side flanges 5 forming part of the seal casing.

It will, of course, be understood that only one 50 shoe, namely the end shoe, has been illustrated and described and that a plurality of supporting shoes, similar to the shoe 10-12, may be engaged beneath the core plate 2 and the filler board 3, at spaced intervals. If preferred, the 55 end units may be tied to the core plate 2 and the filler board 3 by means of tie wires 13. The tie wires 13 are engaged through apertures in the steel plate 4 and through apertures provided in the core plate 2 and the filler board 3. The 60 ends of the tie wires are twisted together to tightly draw the seal unit against the end of the expansion joint.

With the end seal in position as illustrated in Figure 1, the side flanges 5 and the anchoring wings 6 are embedded in the adjacent road slabs 1 thereby holding the rubber sealing pad 5 tightly clamped against the outer end of the expansion joint to seal the same.

With the expansion of the road slabs 1 due to 70 temperature changes, the road slabs expand toward one another thereby compressing the filler board 3 producing a compression of the end seal, causing the side flanges 5 to move toward one another, thereby bulging the steel plate 4 outwardly as illustrated in Figure 3. With this

compression of the seal casing the inherently expandable sealing pad 5 automatically acts to fill the space within the seal casing thereby maintaining the seal against the end of the compressed expansion joint. 5

When the road slabs 1 contract and move away from one another, the side flanges 5, being anchored in the slabs, also move farther apart thereby tensioning the seal casing causing the plate 4 to bend inwardly toward the end of the expansion joint tending to flatten out the seal pad 5 to press the same against the end of the expansion joint to maintain the required seal at the end of the expansion joint. 10

It will, of course, be understood that various 15 details of construction may be varied through a wide range without departing from the principles of this invention and it is, therefore, not the purpose to limit the patent granted hereon otherwise than necessitated by the scope of the appended claims. 20

I claim as my invention:

1. The combination with an expansion joint embedded between concrete road slabs, of an end seal for the expansion joint comprising a 25 casing spanning the end of the expansion joint and projecting into the end faces of the adjacent road slabs, and an inherently expansible seal pad in the casing in sealing contact with the outer end of the expansion joint and overlapping the 30 expansion space between the road slabs.

2. The combination with an expansion joint embedded between concrete road slabs, of an end seal for the expansion joint comprising a casing anchored in the ends of adjacent road slabs and 35 spanning the end of the expansion joint, and an inherently expansible seal pad in the casing in sealing contact with the end of the expansion joint and overlapping the expansion space for maintaining a seal with the road slabs both with 40 the expansion and contraction of the road slabs due to temperature changes.

3. The combination with a transverse joint embedded between concrete road slabs, of an end seal for the joint comprising a casing spanning 45 the end of the joint and anchored in the end faces of adjacent road slabs, channel means connected to said casing for supporting the casing prior to the pouring of the concrete to form the road slabs, and a sealing pad in the casing 50 extending across the end of the channel means and said road joint to maintain a seal therewith.

4. A transverse road joint end seal anchored in road slabs on adjacent sides of the road joint, said joint seal comprising a casing, anchoring 55 means thereon anchored in the end faces of the adjacent road slabs, a support for the casing, means for tying the casing to the road joint, and a sealing material enclosed by the casing and compressed against the end of the road joint and overlapping the outer sides of the road slabs to maintain a seal at the outer end of the road joint both with the compression and the expansion of the road slabs.

5. The combination with a transverse road 60 joint embedded between concrete road slabs, of an end seal for the joint comprising a metal plate, side flanges integrally formed thereon, anchoring members integrally formed on the side flanges and embedded in the outer end faces of 65 the concrete road slabs, means for supporting the plate and side flanges in position, a sealing pad enclosed by the plate and the side flanges and held in sealing contact with the outer end 70 of the road joint and the end faces of the road 75

slabs, and adjustable means connecting the plate and the pad with the road joint.

6. The combination with a transverse road joint embedded between concrete road slabs, of 5 a seal casing anchored to the road slabs and embedded between the road slabs and the road shoulder, and an inherently expandible and compressible sealing pad in the casing held in sealing contact with the outer end of the joint and in 10 contact with the outer end surfaces of said road slabs.

7. The combination with a joint embedded between concrete road slabs, of means for spanning the end of the joint and anchored in the outer 15 end faces of the adjacent road slabs for operation thereby, and a precompressed sealing means enclosed by the spanning means and held in resilient sealing contact with the end of the joint and expandible to maintain a complete filling of 20 the spanning means with the compression and the expansion thereof due to the movements of the road slabs caused by temperature changes.

8. A road joint end seal comprising a metal 25 plate, side and bottom flanges integrally formed thereon, anchoring members formed on the side flanges, and an inherently expandible sealing pad adjacent one side of the plate supported on the bottom flanges between the side flanges.

9. A road joint end seal comprising a metal 30 plate, side flanges integrally formed thereon anchoring members formed on the side flanges, an

inherently expandible sealing pad adjacent one side of the plate and between the side flanges, side base flanges formed on said metal plate and projecting beneath the pad, and a middle base flange on said metal plate projecting beneath the 5 road joint.

10. A road joint end seal comprising a metal plate, side flanges integrally formed thereon, anchoring lugs integrally formed on the side flanges, base flanges integrally formed on the 10 bottom edge of said plate, a sealing pad adjacent one side of the plate and between the side flanges thereof and supported on said base flanges, and a supporting shoe connected with one of the base flanges and shaped to assist in supporting a road 15 joint in position with the end seal in sealing contact with the end of said joint.

11. The combination with a road joint and an end seal therefor, said end seal comprising a casing plate, side flanges integrally formed 20 thereon, anchoring lugs formed on the side flanges, base flanges formed on the bottom of the plate, a sealing pad adjacent one side of the plate and enclosed between the side flanges thereof and in sealing contact with the outer 25 end of the joint, means for connecting the plate and the pad with the joint, and a supporting shoe for the joint connected with one of the plate base flanges.
